UNITED STATES PATENT OFFICE

99,666

DESIGN FOR A COMBINED TABLE AND COOKING GRILL

Harold M. Schwartz, New York, N. Y.

Application March 21, 1936, Serial No. 61,725

Term of patent 3½ years

To all whom it may concern:

Be it known that I, Harold M. Schwartz, a citizen of the United States of America, residing in city of New York, county of New York, and State of New York, have invented a new, original, and ornamental Design for a Combined Table and Cooking Grill, of which the following is a specification, reference being had to the accompanying drawing, forming part thereof.

The figure in the drawing is a perspective view of a combined table and cooking grill showing my new design.

A is a cooking grill inserted in the top portion of the table.

I claim:

The ornamental design for a combined table and cooking grill substantially as shown and described.

HAROLD M. SCHWARTZ.
